(57) **CLAIM**

The ornamental design for a wireless entrance communication device, as shown and described.

DESCRIPTION

FIG. 1 is a front perspective view of a preferred embodiment of the wireless entrance communication device according to the present design;

FIG. 2 is a front elevational view of the wireless entrance communication device of FIG. 1;

FIG. 3 is a rear elevational view of the wireless entrance communication device of FIG. 1;

FIG. 4 is a right-side elevational view of the wireless entrance communication device of FIG. 1, the left-side elevational view being a mirror image thereof;

FIG. 5 is a top plan view of the wireless entrance communication device of FIG. 1; and,

FIG. 6 is a bottom plan view of the wireless entrance communication device of FIG. 1.

In the drawings, dashed lines depict environmental subject matter only and form no part of the claimed design.

1 Claim, 5 Drawing Sheets

Related U.S. Application Data

a continuation of application No. 29/595,337, filed on Feb. 27, 2017, now Pat. No. Des. 830,871.
